UNITED STATES PATENT OFFICE.

FRANK W. FICK, OF AMSTERDAM, NEW YORK.

SPRING-MOUNTING IMPLEMENT.

Application filed November 25, 1921. Serial No. 517,710.

To all whom it may concern:

Be it known that I, FRANK W. FICK, a citizen of the United States, residing at Amsterdam, in the county of Montgomery and State of New York, have invented certain new and useful Improvements in Spring-Mounting Implements, of which the following is a specification.

This invention relates to implements for placing helical springs in their casings or barrels.

The object of the invention is to provide a tool so constructed that a coiled helical spring may be held coiled and positioned where desired and after having its ends connected as desired and the binding wire released, the tool may be readily removed without disturbing the spring.

Another object is to provide a tool of this character having spring gripping jaws and equipped with self centering means to effect an even bearing at any and every angle of the jaw carrying it.

Another object is to provide such a tool with means for releasing and withdrawing the tool from the spring barrel after the spring has been properly adjusted.

Another object is to provide a trigger releasable device for locking the tool firmly to the spring and to provide for the quick gripping of the tool on the spring and its quick release without the use of any screws or bolts.

With these and other objects in view, the invention consists in certain novel features of construction as hereinafter shown, described and claimed.

In the accompanying drawings:—

Figure 1 represents a perspective view of a spring casing or valve with this improved implement shown applied and in the act of holding the spring in the barrel ready for its connection.

Fig. 2 is a side elevation of the tool with the parts in the position assumed when ready for gripping a spring.

Fig. 3 is a similar view with the parts in the position assumed when removing the tool from the barrel.

Fig. 4 is a central vertical section showing the interior construction of the parts.

Fig. 5 is an enlarged detail perspective view of the slide carrying jaw with parts broken out and in section.

Fig. 6 is a plan view or end elevation of 55 the tool.

Fig. 7 is a transverse section taken on the line 7—7 of Fig. 2.

Fig. 8 is a rear elevation thereof, and, Fig. 9 is a detail sectional view taken on 60 the line 9—9 of Fig. 2.

The tool constituting this invention, while adapted for use in holding coiled helical springs and placing them in any desired position, is primarily designed for use in 65 connection with the springs of talking machines. As is well known by those familiar with the art, all springs furnished for talking machines or phonographs are sent from the factory inclosed in a metal ring and 70 during the operation of placing the spring in its barrel it is necessary to remove the ring just before the spring is slipped into place. Ordinarily this requires a large amount of 75 work and considerable pressure by the human hand and oftentimes the spring slips and consequently has to be rewound. The tool constituting this invention is so constructed that in one operation, it will hold the spring in place to permit the metal ring 80 to be removed and will allow the operator to slip the spring into its proper position in the machine and by the use of the gravity trigger employed, as will be hereinafter more fully described, holds the spring in 85 its proper position until the fastening thereof is successfully completed and then on the release of the trigger by the operator the jaw of the tool will automatically open and release the spring so that the instrument 90 may be removed from the spring and taken out of the barrel without in any way injuring the spring or the barrel.

The tool herein shown and described, is 95 constructed for the use above stated, but obviously it may be made in various sizes to adapt it for use with springs of different sizes, such for instance, as those of a watch or clock.

In the embodiment illustrated, the tool 1 100 constituting this invention is shown constructed for use in mounting a coiled helical spring S in a deep spring barrel B, although obviously it may be used in connection with barrels of different sizes or depths.

This tool 1 comprises two cooperating gripping jaws 5 and 10 pivotally connected to move toward and away from each other as

will be presently more fully described. The jaw 5 has its front end laterally offset outward to provide a seat on its inner face for the self-centering attachment 6 which is 5 loosely mounted on said jaw being shown provided with a laterally extending shank 7 which extends loosely through an aperture 8 in the jaw 5 and is connected therewith by a pin 9 extending transversely 10 through the outer end of the shank 7 and resting on the outer face of the jaw spanning the aperture 8 therein. This self-centering device 6 has a flat article engaging face, while its rear face is inclined outwardly from its shank 7 toward its end to adapt it to rock on the inner face of the jaw 5 so as to conform to the spring to be gripped thereby and provide an even bearing at any and every angle of the jaw. 15

20 The jaw 5 is shown made integral with a right angularly extending handle 4 which is bowed longitudinally outward and provided on its rear edge with a laterally extending integral arm 3 which is curved longitudinally and provided on its rear edge near its front end with ratchet teeth 2, for a purpose presently to be described.

It will thus be seen that the jaw 5 and its handle 4 form a substantially L-shaped member which cooperates with a member 15 the handle portion 16 of which is substantially parallel with the handle 4 of member 5, said handle 16 having an aperture 17 extending edgewise therethrough for the passage of the arm 3 of the handle 4, as is shown clearly in Figs. 2 and 4. Pivotally mounted in the aperture 17 is a pawl 18, the body of which is located outside said aperture while the shank 19 thereof extends into the aperture 40 and is pivotally mounted therein. This pawl 18 has a nose 20 for engagement with the ratchet teeth carried by the arm 3 as is shown clearly in Fig. 4, and at its other end has a finger grip 21 for releasing the pawl 45 from the ratchet.

The member 15 has a bifurcated head 22 at its inner or front end, the furcations 23 of which extend laterally from the front face of the head and are designed to receive 50 between them the jaw member 5 and the shank or arm 11 of jaw 10, all of which are pivotally connected by the pivot 24 passing through the free ends of the furcations 23 and through the members 5 and 10 at their 55 junction with their arms 4 and 11 respectively, (see Fig. 4).

The member 11 adjacent its connection with jaw 10 has a recess 12 in one side face thereof to receive the jaw member 5 as is 60 shown clearly in Fig. 4. The free end of said arm 11 is flattened out and lies between members 15 and 4 being designed to be engaged by member 15 which controls the closing movement of jaw 10 by engaging 65 said lever arm 11 and moving the jaw to-

wards jaw 5. The jaw member 10 is heavier than arm 11 so that when the member 15 is moved out of engagement with the arm 11, the jaw 10 will swing by gravity into open position as shown in Fig. 3. 70

The jaw 10 is concavo-convex in cross section and has its outer side edges bevelled as shown at 10^a with which is designed to be engaged gripping fingers or guide lugs 26 carried by a slide 25, which is mounted to 75 reciprocate on jaw 10 and is designed as an ejector or release device for the spring when the jaws 5 and 10 have been opened and it is desired to withdraw the tool from the spring barrel without changing the position 80 of the spring. The fingers 26 are formed by slitting the slide 25 transversely and bending down the portions so slit at the ends of the slide to form these fingers and bending upwardly the intermediate portions 85 27 to form upstanding lugs with which are pivotally engaged one end of two links 28 and 29 arranged at opposite sides of the tool the other ends of said links being pivotally connected with obliquely and rearwardly extending ears 30 carried by the bifurcated head 22 of the members 15. This pivotal connection of the sliding member 25 by the links 28 and 29 with the pivoted member 15 provides for the operation of the slide 90 by the opening and closing of the member 15.

It is obvious that when the member 15 is swung into full open position, as shown in Fig. 3, that the slide 25 will be at its extreme forward movement, and when it is 100 in closed position, as shown in Fig. 4, said slide will be at its extreme inward position.

The jaws 5 and 10 may be of any desired length according to the depth of the barrel or casing B in connection with which 105 the tool is to be used, the deeper the barrel the longer these jaws will be since the tool is designed to insert a spring S in the bottom of the casing as is shown clearly in Fig. 1, and to do this, it is necessary that 110 these jaws be long enough to reach the bottom and to have the handles 4 and 16 extend laterally over the upper edge thereof.

When the jaws are in gripping position and the tool held as shown in Figs. 1, 2 and 5, the gravity pawl 18 will drop into engagement with the teeth 2 of the ratchet 3 and lock the jaws against opening, so that when they are gripped around the coiled spring as shown in Fig. 1, the tendency of the spring to unwind will have no effect on the jaws and cannot open them until said pawl is released. 115

When it is desired to release the jaws from the spring, the finger grip 21 of the pawl is depressed to disengage the nose 20 thereof from the ratchet and the member 15 may be then swung away from the handles 4 thereby permitting the handle 4 to drop down and the jaw 5 to open thus 130

releasing the spring. The further opening of the member 15 will cause the links 28 and 29 to straighten out and move forward carrying with them the releasing slide 25 which moves forward against the upper edge of the coiled spring S thereby forcing the tool upward out of engagement with the spring and permitting it to be removed without in any way affecting the 10 position of the spring.

From the above description, it is thought that the operation of the tool will be obvious, it being understood that the spring S to be placed in the barrel B is first 15 gripped by the jaws 5 and 10 in advance of the slide 25, the concave inner face of jaw 10 being adapted to fit the outer coil of the spring and the centering shoe 6 will engage the inner coil as shown in Fig. 1 20 and when so engaged the handles 4 and 16 are brought together to clampingly secure the jaws and are locked by the pawl 18 dropping into engagement with one of the teeth of the ratchet 3. The spring may 25 be then inserted in the barrel as shown in Fig. 1 and after the ends thereof have been secured as desired, the tool is removed by releasing the trip member 18 and permitting handle 4 to drop down and thereby 30 swing jaw 5 away from the spring and on the further opening of the member 15 cause the slide 25 to move forward and the tool be lifted upward out of engagement with the spring, so that it may be removed from 35 the barrel without interfering with either the spring or the barrel.

From the above, it will be observed that the device may be quickly applied to or released from a spring by simply engaging 40 the pawl 18 with the ratchet 3 or releasing it therefrom and that no screwing or unscrewing of bolts or screws is necessary.

The preferred embodiment of the invention is disclosed in the drawings and set 45 forth in the specification, but it will be understood that any modifications within the scope of the claimed invention may be made in the construction without departing from the principle of the invention or sacrificing 50 any of its advantages.

I claim:—

1. In a device of the class described, pivotally connected clamping jaws, handle members, one rigidly connected with one jaw 55 and the other pivotally connected with the other jaw and with said fixed handle, said pivoted jaw having an arm located in the path of said pivoted handle whereby movement of said handle in one direction will 60 close said jaw and movement in the other direction will release it, and means for locking said handles to hold the jaws in clamping position.

2. A device for inserting springs in their 65 casings and the like comprising handle

members pivotally connected at one end to move toward and away from each other, a laterally extending clamping jaw fixedly carried by the pivoted end of one handle, a cooperating clamping jaw having a laterally 70 extending arm at its rear end and pivotally connected at its junction with said arm to the handle having the fixed jaw at the junction thereof with said jaw, another handle member bifurcated with the furcations thereof straddling said jaws at their pivotal connection and pivotally connected therewith, said jaw arm being mounted in the path of said pivoted handle and its opening and closing control thereby, and a pawl and 80 ratchet locking mechanism located between said handle to lock the jaws in clamping position.

3. In a device of the class described, pivotally connected clamping jaws, handle members, one rigidly connected with one jaw and the other pivotally connected with the other jaw and with said fixed handle, said pivoted jaw having means located in the path of said pivoted handle whereby 90 movement of said handle in one direction will close said jaw and movement in the other direction will release it, means for locking said handles to hold the jaws in clamping position, and means slidable on 95 one of said jaws operable on the release of said handle to move outward and force the implement away from the spring in connection with which it is to be used.

4. A device for inserting springs in their casings and the like comprising clamping jaws, means for locking and releasing said jaws, and means operable on the opening of the jaws to disconnect the device from the spring in connection with which it is used. 100

5. A device of the class described comprising pivotally connected clamping jaws, means for holding said jaws in closed position, and tool releasing means slidably mounted on one jaw and operable on the opening of the jaws to disconnect the tool from the spring. 105

6. A device of the class described comprising pivotally connected clamping jaws, means for locking and releasing said jaws, means for disconnecting said device from the spring in connection with which it is used, and a link and lever connection with said separating means operable on the opening of the jaws. 115

7. A tool of the class described comprising gripping jaws, means operating said jaws, self centering means carried by one of said jaws, and means for disengaging the tool from the article gripped thereby carried by the other jaw. 120

In testimony whereof, I affix my signature hereto.

FRANK W. FICK.
